UNITED STATES PATENT OFFICE.

WILLIAM J. HUGHES, OF CHICAGO, ILLINOIS.

SPRIT-LEVEL.

1,093,801.

Specification of Letters Patent. Patented June 2, 1914.

Application filed December 27, 1912. Serial No. 809,073.

To all whom it may concern:

Be it known that I, WILLIAM J. HUGHES, a citizen of the United States, residing at Chicago, in the county of Cook and State of Illinois, have invented certain new and useful Improvements in Spirit-Levels, of which the following is a specification, reference being had to the accompanying drawings.

10 This invention relates to new and useful improvements in spirit levels and more particularly to a level for use in dark corners and the primary object of the invention is to provide means in connection with the level for providing a light directed to the bubble glasses and the work to which the device is applied.

15 A further object of the invention resides in providing a stock having a central longitudinal bore and also provided with channel-ways communicating with said bore and terminating in the upper and lower faces of the stock.

20 Still another object of the invention resides in providing a device which is simple and durable in construction, inexpensive to manufacture and one which will be very efficient and useful in operation.

25 With these and other objects in view, the invention consists in the novel features of construction, combination and arrangement of parts as will be hereinafter referred to and more particularly pointed out in the specification and claims.

30 In the accompanying drawing forming a part of this application, Figure 1 is a side elevation partly in section of a device constructed in accordance with my invention. Fig. 2 is an end elevation of the device. Fig. 3 is a transverse section therethrough as seen on line 3--3, Fig. 1. Fig. 4 is a similar view as seen on line 4--4, Fig. 1. Fig. 5 is a section through the device as seen on line 5--5, Fig. 1; and Fig. 6 is a plan view of 45 the device.

40 In describing my invention, I shall refer to the drawing in which similar reference characters designate corresponding parts throughout the several views and in which--

50 1 indicates the stock of a spirit level, the same having the sight openings 2 and 3 extending transversely therethrough and suitably mounted in the walls of the openings

55 2 and 3, are the bubble glasses or tubes 4.

55 My invention contemplates the provision

of a means in connection with the spirit level for directing the light on the bubble glasses and, at the same time, directing the light on the work to which the device is applied and, to this end, the stock is provided with a central longitudinal bore 5, which communicates with the transverse sight openings 2 and 3. This bore terminates at the one end in a pocket 6, which opens on the one side of the stock and the purpose of which will be hereinafter and more particularly set forth. The opposite end of this bore terminates directly in the wall of the side opening 3 and the end of the stock adjacent which this last mentioned opening is provided, has a chamfered socket 7 formed therein which terminates in the wall of the opening 3 opposite to and in alinement with the bore 5. This last mentioned end of the stock forms in reality, the upper or top end 70 of the device when set up for use on its end.

75 Adapted to be mounted in the pocket 6, is a flash light 8, of the usual or any preferred design and a hinge door 9 is provided for this pocket which retains the flash light in 80 position. This door may be provided with a slot, as shown at 10, whereby the circuit closing member of the flash light may be projected therethrough for ready operation by the mechanic. When the flash light is 85 applied to use, it will be seen that the rays of light therefrom will be directed through the bore 5 of the socket, so that the bubble glasses arranged in the sight openings 2 and 3, may be readily observed in dark places. 90 I have also constructed the stock so as to permit the rays of light to also be directed on the work to which this device is applied, so that marks or the like thereon may be readily observed. To this end, channel-ways 11 are provided, which afford communication between the upper and lower faces of the stock and the bore 5 and extend for the greater portion of the length of the stock, as clearly shown in Fig. 6 of the 100 drawing. Thus, as the rays of light are directed through the bore 5, from the flash light, the same will also be directed through these channel-ways 11 and the work to which this device is applied may be readily observed in dark nooks and corners. These channel-ways 11 are preferably inclined to 105 toward the side faces of the stock, as clearly shown in Fig. 3 of the drawing.

110 It will be readily understood that my de-

vice may be used as an ordinary flash lamp, as the rays from the flash light 8 pass through the bore 5 and outwardly from the stock through the opening 7 in the end thereof. The walls of the opening 7 are beveled outwardly from the end of the bore to the extremity of the stock so that the rays of light will be deflected to cover a relatively larger area than the size of the stock.

From the foregoing description of the construction of my improved device, the manner of applying the same to use and the advantages thereof will be readily understood and it will be seen that I have provided an improved spirit level which is simple and durable in construction, inexpensive to manufacture and one which will be very efficient and useful in operation.

While I have particularly described the elements best adapted to perform the functions set forth, it is obvious that various changes in form, proportion and in the minor details of construction may be resorted to without departing from the spirit or sacrificing any of the principles of the invention.

Having thus described this invention, what I claim is:—

1. A spirit level comprising a stock having transverse sight openings therein and also provided with a central longitudinal bore communicating with said openings and terminating at its one end in a pocket formed adjacent one end of the stock, bubble tubes mounted in the walls of said sight openings, the end of said stock opposite that having the pocket therein being provided with a socket terminating in one wall of the adjacent sight opening and in aline-

ment with the bore, and a flash light mounted in the aforesaid pocket.

2. A spirit level comprising a stock having transverse sight openings therein and provided with a central longitudinal bore 45 communicating with said openings and terminating at its one end in a pocket adjacent one end of said stock, said stock being also provided with channel-ways affording communication from a pair of opposite faces of 50 the stock, to said bore and extending for the greater portion of the length of said stock, bubble tubes mounted in the walls of said sight openings, and a flash light mounted in the aforesaid pocket.

3. A spirit level comprising a stock having a plurality of transverse sight openings therein and also having a central longitudinal bore communicating with the openings and terminating at its one end in a pocket 60 formed adjacent one end of said stock, said stock being also provided with a pair of channel-ways affording communication between a pair of opposite side faces of the stock and said bore and extending for the 65 greater portion of the length of said stock, the end of said stock opposite that adjacent which the pocket is formed being provided with a socket terminating in the adjacent sight opening and in alinement with said 70 bore, bubble tubes mounted in the walls of said sight openings, and a flash light mounted in the aforesaid pocket of the stock.

In testimony whereof I hereunto affix my signature in the presence of two witnesses.

WILLIAM J. HUGHES.
